CLAIM

The ornamental design for a combined dowel pin and parting guide for use in the construction of dental prosthetics.

DESCRIPTION

FIG. 1 is a front elevational view of a combined dowel pin and parting guide for use in the construction of dental prosthetics showing our new design;

FIG. 2 is a right side elevational view thereof, the left side being a mirror image of that shown;

FIG. 3 is a rear elevational view thereof;

FIG. 4 is a top plan view thereof; and

FIG. 5 is a bottom plan view thereof.

FIG. 3

FIG. 5

FIG. 2

FIG. 1

FIG. 4
